UNITED STATES PATENT OFFICE.

GILBERT R. COLEMAN, OF JERSEY CITY, NEW JERSEY, ASSIGNOR OF ONE-HALF TO
THOMAS F. KENT, OF NEW YORK, N. Y.

APPLICATION OF BABBITT AND LINING METALS TO THE SURFACE OF RAILROAD AND OTHER JOURNAL BEARINGS.

Application filed July 27, 1923. Serial No. 654,073.

To all whom it may concern:

Be it known that I, GILBERT R. COLEMAN, a citizen of the United States, and a resident of Jersey City, in the county of Hudson and State of New Jersey, have invented certain new and useful Improvements for the Application of Babbitt and Lining Metals to the Surface of Railroad and Other Journal Bearings, of which the following is a specification.

My invention relates to new and useful improvements in devices for the application of Babbitt and lining metals to the surface of railroad and other journal bearings. Its object is to provide such a device which will operate more efficiently, provide a better and more even lining and at the same time increase the speed at which the bearings can be lined. Heretofore mandrels have been used in connection with the lining of bearings but have been used with separate and independent side pieces which have had to be hammered into place. In my invention the side pieces are coating and are forced into place by operation of the same means, maintaining substantial parallelism with one another throughout. I have also provided my device with a series of mandrels mounted on a revoluble table so that the operator can apply the lining on one mandrel, turn the table, repeat the operation on the successive mandrels and by the time the original mandrel is returned to him the lining will have been sufficiently solid to allow for the removal of the bearing. I have also provided each of the mandrels with a simple working clamp so that the journal bearing can be quickly held in place and easily removed at the proper time. I show in addition in the drawings and description various details of my preferred construction. In so describing my preferred form, I do not, however, limit myself to such construction, the scope of my invention being pointed out in the claims.

Referring to the drawings,

Fig. 1 is a side elevation of my apparatus; and

Fig. 2 is a plan view of same.

The preferred form of my apparatus is provided with a stand 1 on which is mounted a ball thrust bearing 2 carrying table 3 free to rotate on the stand 1. The table 3 carries preferably four openings into which man-

drels 4^a, 4^b, 4^c and 4^d are fitted. The mandrel 4 is made of an air cooled hollow construction so as to permit the free passage of air from the bottom to the top and carries internally cast fins 5 in order to give a great cooling area, the fins running vertically. The mandrel is fitted with two side pieces 6, 6. These side pieces are designed so that they bear on the outer surface of the mandrel at only two points 7, 7' and a space 8 is left between the side pieces and the mandrel which also affords free passage of air and assists in the cooling. The side pieces may be fluted if desired. The side pieces are held in contact with the face of the mandrel by means of bar 8. Bar 8 extends through elongated holes 9 (shown in dotted lines in Fig. 2) in the sides of the mandrel. The bar 8 carries a stud 10. The stud 10 bears on the side pieces 6. A coil spring 11 and a nut 12 hold the side pieces 6 through the stud 10 in contact with the surface of the mandrel. A housing 13 protects stud, nut and spring from being fouled with molten metal. The bar 8 has a lateral movement on account of the elongated holes 9. It is actuated laterally by means of a screw 14 operating in the hole 15' provided in the bar 8. By a circular movement of the hand wheel 15 operating the screw 14, lateral movement is imparted to sides pieces 6. The position of the side pieces regulates the thickness of the Babbitt or other metal imparted to the journal bearing 20. A lock nut 16 prevents lateral movement of screw 14 with respect to the mandrel 4. The side pieces bear on the mandrels at their end portions only, namely, at 7 and 7'. In addition to affording an air cooling space, this construction forces the side pieces to stay substantially parallel to the vertical face of the mandrel 1 and to each other. It will be seen from the above description that by means of hand wheel 15 a quick regulation of the thickness of lining to be applied is afforded.

The journal bearing 20 to be lined is placed in the usual position against the mandrel and is held in place by means of clamp 21. Clamp 21 on its bottom side is provided with a rack 22. A gear 23 engages with this rack and is carried on the shaft 24. A part of the clamp 21, its underside rack and the gear 23 are carried in a housing 25. In Fig. 1 this housing is broken away to show the

construction of elements 21 to 24 inclusive. To the shaft 24 is fixed a weighted handle 26. A movement of handle 26 in the direction of the arrow shown in Fig. 1 rotates the shaft 24 and gear 23 and causes clamp 21 through engagement of the rack to be forced forward and hold the journal bearing in place. Adjustment of the clamp 21 can be made by adjusting the mesh of the rack 22 to the gear 23. In order to provide accessibility the housing 25 is provided with a detachable cover 27. The weighted handle 26 when the clamp is in position maintains pressure on the railroad or other bearing to be lined and holds said bearing securely to side pieces 6. The lining metal is applied in the space between the journal bearing at 20 and the face of the mandrel. The pressure of the lining metal when applied there is not great enough to cause any movement of the journal bearings on account of the weighted handle. With the journal bearing 20 in position and the clamp with the weighted handle 26 as shown, the Babbitt or lead lining is poured in and the table 3 given a quarter turn to the left by the operator. The lining operation is then successively repeated. When the original mandrel returns to the operator, the lining is sufficiently solid to permit the removal of the bearing and another bearing is inserted in its place and clamped there as previously described. In this way a continuous cycle of operation is provided.

As previously stated the table 3 is provided with a suitable number of openings to carry the mandrel. These openings have a lower lip 30, shown in dotted lines in Figs. 1 and 2, running around the lower part. The base 31 on each mandrel fits into the opening and is held by means of the lip 30. The base 31 of the mandrel when inserted in the opening forms a part of the table 3. After the mandrel has been placed in position it is fixed by means of off set washer 32 bearing on a part of the lip 30 and on the base of the mandrel and is held by means of cap screw 33. The mandrel can therefore be easily taken out and another one substituted for it. Mandrels of different sizes can therefore be used interchangeably in my device without requiring any reconstruction. It is quite important that when the mandrel is in position the clamp 21 should bear on the central point of the bearing which is being lined. When different sized mandrels are lined I adjust the height of the mandrel to bring the central point of the bearing opposite the clamp piece by either increasing or decreasing the size of the metal pad 34. I have referred to the clamping means as being brought to bear upon the central point of the bearing. This is usually proper but in the case of some bearings in which the weight and mass is not evenly distributed

another point other than the central one of the bearing may be the suitable point at which the clamp should bear upon such bearing. I have described the above adjustment as being made by an adjustment of the mandrel to the clamp. In some cases it may be easier to adjust the height of the clamp itself.

I have therefore provided a device for the application of Babbitt or other lining to journal bearings which is easy of operation and in which the thickness of the metal can be regulated at will and at the same time such metal will be evenly distributed on the surface of the bearing. The quick adjustment and clamping of the journal bearing and the easy regulation of the thickness of the lining to be applied by means of the hand wheel and side pieces and the continuous cycle of operation permits a much greater output and reaches a better result, because of the even distribution of the lining on the surface of the bearing. Mandrels of different sizes may be used interchangeably in my device.

What I claim as new and desire to secure by Letters Patent of the United States is:—

1. In an apparatus for lining bearings, a mandrel provided with slots, a member passing through said slots, side pieces carried by said member, an element adjustably connecting said mandrel and said side pieces, and means to hold said bearings in engagement with said side pieces.

2. In an apparatus of the character described, a mandrel, coacting side pieces engaging said mandrel, a bar passing through said mandrel and secured to said side pieces, spring elements between said bar and said side pieces, and means for adjusting said bar with respect to said mandrel.

3. In an apparatus of the character described, a mandrel, side pieces coacting with said mandrel, a bar extending through said mandrel and attached to said side pieces, a screw member connecting said mandrel and said bar, and means maintaining said side pieces in engagement with said mandrel.

4. In an apparatus for lining journal bearings of the character described, a mandrel provided with coacting side pieces, said side pieces bearing on said mandrel at their end portions only and means actuating said side pieces.

5. In an apparatus for lining journal bearings of the character described, a mandrel having an air cooled interior and provided with coacting side pieces, said side pieces bearing on said mandrel at their end portions only and providing an air cooling space between said ends, and means actuating said side pieces.

6. An apparatus for lining journal bearings comprising a revoluble table, a series of mandrels mounted thereon, said mandrels provided with coacting side pieces, said side

pieces being carried by a bar running through said mandrel, said side pieces bearing on said mandrel at their end portions only, means affixing said side pieces to the 5 ends of said bar, a protective housing for said means, said bar being actuated by a screw and wheel and means for removably holding journal bearings in place with respect to said mandrels comprising a clamp 10 and weighted means operating said clamp.

7. An apparatus for lining journal bearings of the character described comprising a revoluble table, means for supporting same, said table having openings therein 15 adapted to receive mandrels, a lip running around the lower part of said openings and means for fixing said mandrel in position.

8. An apparatus for lining journal bearings of the character described comprising a revoluble table, means for supporting same, said table having openings therein adapted to receive mandrels, a lip running around the lower edge of said openings, and releasable locking elements adapted to 20 25 cure said mandrels to said table.

9. In an apparatus for lining journal bear-

ings comprising a revoluble table, means for supporting same, a series of openings in said table adapted to hold mandrels of different sizes interchangeably, means for removably clamping journal bearings in place with respect to said mandrels and means for respectively adjusting said mandrels and said clamping means with respect to one another so as to have said clamping means 30 35 bear upon said journal bearing at the suitable point.

10. In an apparatus for lining journal bearings comprising a revoluble table, means for supporting same, a series of openings in 40 said table adapted to hold mandrels of different sizes interchangeably, means for removably clamping journal bearings in place with respect to said mandrels, said mandrels having a base portion thereof adapted to 45 give to said mandrel a height such that said clamping means will bear upon the suitable point of the bearing to be lined.

In testimony whereof, I have signed my name to this specification.

GILBERT R. COLEMAN.
